UNITED STATES PATENT OFFICE.

FREDERICK E. CHAPMAN, OF MIDDLETOWN, CONNECTICUT.

ALARM.

Application filed November 25, 1922. Serial No. 603,197.

To all whom it may concern:

Be it known that I, FREDERICK E. CHAPMAN, a citizen of the United States, and a resident of Middletown, in the county of 5 Middlesex and State of Connecticut, have invented new and Improved Alarms, of which the following is a specification.

My invention relates to the class of devices especially designed to give warning 10 of the presence of fire or of a burglar, and an object of my invention, among others, is to provide a device of a reliable character that shall operate both as a fire and as a burglar alarm.

One form of device embodying my invention and in the construction and use of 15 which the objects herein set out, as well as others, may be attained, is illustrated in the accompanying drawings in which—

Figure 1 is a diagrammatic view illustrating the arrangement of my improved alarm.

Figure 2 is a detail view, scale enlarged, illustrating one of the alarms, with parts broken away to show construction.

Figure 3 is a detail view, scale enlarged, showing another of the alarms.

Figure 4 is a view of a fragment of an alarm showing one manner of operating it.

Figure 5 is a detail view illustrating the 30 construction and operation of the bell sounders.

My improved fire and burglar alarm comprises a system including a number of alarm devices that may be located in various positions and that may be connected one with another to operate independently or simultaneously as may be desired, such system being diagrammatically illustrated in Figure 1 in which there is an alarm designed for 35 operation under conditions of fire and including a base 6 having a disc 7 rotatably mounted thereon with a connection 8 extending from the disc to an actuating weight 9, shown in dotted outlines in Figure 3, said weight being supported on a trap 10 pivotally mounted on a case 11 and extending underneath said case in which the weight 9 is located. This trap embodies a holder 12 rigidly connected therewith and extending 40 into a pan 13, to the bottom of which it is secured by any suitable solder that will fuse under comparatively low temperatures. In order to insure the fusing of the solder 45 the pan may be supplied with some substance that will ignite under a comparatively low temperature. An arrester 14 in

the form of a flexible connection extends from the weight 9 to a flexible support 15 secured to the base 6. An actuating connection 16 extends from the disc 7 to any device to be actuated thereby, as shown in Figure 1 this connection extending to a bell alarm 17 and also to a second alarm device similar to that just above described.

The bell illustrated herein is supported on 65 a base 18 and comprises a gong 19 secured to the base to be sounded by a striker 20. This striker is pivotally mounted in a case 21 and is spring pressed toward the bell as shown in Figure 5. A strut 22 is interposed 70 between the tail of the striker 20 and a wall of the case, this strut being connected with or secured to the connection 16.

From this construction it will be seen that when the trap 10 is released under abnormal 75 heat conditions the weight 9 will be released and thereby the disc 7 will be rapidly rotated, pulling upon the connection 16 and sounding the gong 19. The pull of the weight will be stopped by the arrester 14 80 without undue shock upon the apparatus. The connection 16 is a branched connection, and one branch extends to a retainer 23 interposed between a pivotally mounted trap 24 and a support 25 to retain the trap in its 85 raised position, as shown in Figure 1. This trap supports a weight 26 as hereinbefore described, located in a case 27, said weight being connected with a disc 7, as hereinbefore described, said disc being connected in 90 the same manner as hereinabove set forth with a second bell alarm 17.

The weight 26 in the case 27 has a recess in its end that receives a spring 28 that, when the trap is released, by operation of 95 the jointed retainer 23, will strike the button 29 of a sounding alarm 30, as herein shown in the form of a horn.

By means of these second alarms and the connections above noted the alarms may be 100 given in places remote from that in which alarm first above mentioned is located.

Either of the alarms may be utilized for operation to give warning of a burglar, as shown in Figure 1, the alarm embodying a 105 case 27 being connected by a flexible member 31 with a door 32 whereby said alarm will be sounded should any attempt be made to open the door.

In Figure 4 I have illustrated another 110 means for releasing the trap 10, this comprising a flexible holder 33 engaging a sup-

port 34 and secured at its ends to posts 35-36, the latter projecting from the bottom of the trap 10. The support 34 has a pan 37 to receive a material that will ignite under low temperature and thereby burn the cord 33 to release the trap 10, the latter supporting a weight as hereinbefore described.

I claim—

1. An alarm comprising a rotatable disc, a connection extending from said disc to an alarm device, a weight connected with said disc, a trap to support said weight and render it inactive, and a releasable holder for said trap adapted to be operated to release the weight and permit operation of the alarm upon rotation of the disc.
2. An alarm comprising a rotatable disc, a connection extended from said disc to an alarm device, a weight connected with said disc, a trap to support said weight and render it inactive, der it inactive, means for operating the trap 35-36, the latter projecting from the bottom of the trap 10. The support 34 has a pan 37 to receive a material that will ignite under low temperature and thereby burn the cord 33 to release the trap 10, the latter supporting a weight as hereinbefore described.
3. An alarm comprising a rotatable disc, a connection extended from said disc to an alarm device, a weight connected with said disc, a trap to support said weight and render it inactive, a releasable holder for said trap, and an alarm to intercept falling movement of said weight.
4. An alarm comprising a rotatable disc, a connection extending from said disc to an alarm device, a weight connected with said disc, a trap to support said weight and render it inactive, a releasable holder for said trap, and a plurality of connections extending from said holder to be operated under different conditions.

FREDERICK E. CHAPMAN.
